Lacy & Lacy, Attorneys

UNITED STATES PATENT OFFICE.

DONALD K. McGINTY, OF MARION, OHIO.

CABLE HANGER.

Application filed September 17, 1921. Serial No. 501,271.

To all whom it may concern:

Be it known that I, DONALD K. McGINTY, a citizen of the United States, residing at Marion, in the county of Marion and State of Ohio, have invented certain new and useful Improvements in Cable Hangers, of which the following is a specification.

This invention relates to an improved cable hanger and one of its objects is to provide a device of this character which may be readily engaged with a supporting messenger wire, embracing a cable for suspending the cable from the wire.

A further object of the invention is to provide a hanger so constructed that the hanger will clamp the messenger wire and will also clamp the cable, preventing play of the cable in the hanger as well as preventing swinging of the hanger upon the wire.

And another object is to provide a device which may be readily detached so that the device may be used over and over again.

Other and incidental objects will appear hereinafter.

In the drawings:

Figure 1 is a perspective view showing a pair of my improved hangers in connection with a messenger wire and cable, the cable being illustrated in dotted lines,

Figure 2 is a sectional view through the device, and,

Figure 3 is a sectional view showing the manner in which the device is applied.

Referring now more particularly to the drawing, I employ a substantially U-shaped hanger body 10 which is preferably formed of suitable resilient sheet metal and is provided with spaced sides 11 and 12. As best shown in Figure 2 of the drawing, the side 11 is curved inwardly at its free end portion to provide a reentrant jaw 13 lying between the sides of the body, and formed in the side 11 is a longitudinally extending medial slot 14 terminating short of the free end of the jaw 13 to define a pintle 15. Near its free end, the side 12 of the body is provided with an opening 16. Swingly mounted upon the jaw 13 is a substantially U-shaped latch 17 which is also preferably formed of suitable resilient sheet metal. At its inner end portion this latch is looped around the pintle 15, as shown at 18, and is thus swingly mounted upon said pintle while at its free

end the latch is bent to define an angularly disposed hook 19, the free end of the latch being adapted to extend through the opening 16 of the arm 12 so that said hook may, as shown, be engaged with the arm. In this connection it should be observed that the latch is freely movable through the slot 14 of the arm 11.

In order to clearly bring out the manner of use of my improved hanger I have, in Figure 1, shown a pair of the devices in connection with a messenger wire 20 and cable 21, the cable being illustrated in dotted lines. In applying the device, the hanger body is first arranged to embrace the cable, the body being held so that the sides 11 and 12 thereof project upwardly from the cable. The latch 17 is then swung to approximately the position shown in Figure 3, when the jaw 13 of the side 11 of the body is engaged over the wire 20. The latch is then swung through the slot 14 over the wire to the position shown in Figure 2, when the free end of the latch is inserted through the opening 16 of the arm 12 of the body and the hook 19 of said latch engaged with the arm. The latch when so disposed, will thus be arranged to extend over the wire 20 forming a jaw cooperating with the jaw 13 to clamp the wire therebetween. At the same time, the latch will serve to hold the hanger body clamped about the cable, the resiliency of the sides 11 and 12 of the body serving to prevent accidental disengagement of the latch. Accordingly, the cable will be tightly held within the hanger while the hanger will grip the messenger wire to prevent swinging of the hanger thereon. I thus provide a highly efficient device for the purpose set forth and, as will be seen, the device may be readily applied or removed by simply manipulating the latch.

Having thus described the invention, what is claimed as new is:

1. A device of the character described including a hanger body having sides one bent at its free end to provide a jaw lying between the sides, there being a slot in one of the sides and an opening in the other of said sides, and a latch swingly mounted upon said jaw for movement through said slot to engage at its free end through said opening, connecting the sides and forming

a jaw to coact with said first mentioned jaw for clamping a supporting element therebetween.

2. A cable hanger consisting of a substantially U-shaped hanger body having one side terminating in a down-turned jaw at its top, and a latch pivoted to the end of said jaw and rising from the pivot between

the jaw and the body side carrying the same whereby to clamp a supporting element to said jaw and thence passing across the body to effect locking engagement at its free end with the free side of the body. 10

In testimony whereof I affix my signature.

DONALD K. McGINTY. [L. s.]
